WINDOW CONSTRUCTION

Russell B. Nelson, Onondaga, N. Y., assignor to
 The O. M. Edwards Company, Inc., Syracuse,
 N. Y., a corporation of New York

Application May 14, 1937, Serial No. 142,656

12 Claims. (Cl. 189—73)

This invention relates to window constructions, particularly to window constructions for railway cars, buses, airplanes, airships and the like, and has for its object a simple and efficient means for holding the window sash assembled in the window frame without the use of screws and the like, and also this means for holding the window sash in the window frame in connection with means for cushioning the sash against shocks and jars and for compensating for misalignments in windows in which the sash may be raised and lowered.

The invention consists in the novel features and in the combinations and constructions hereinafter set forth and claimed.

In describing this invention, reference is had to the accompanying drawings, in which like characters designate corresponding parts in all the views.

Figure 1 is a fragmentary elevation of a window, one which includes a sash that may be raised and lowered.

Figures 2 and 3 are sectional views taken respectively on the planes of lines 2—2 and 3—3, Figure 1.

Figure 4 is an enlarged sectional view of the window frame and sash guide with the demountable side of the window frame partly removed or out of its normal position.

Figure 5 is a fragmentary elevation of a window embodying a stationary sash and cannot be raised and lowered and which is cushioned throughout its entire circumference.

Figure 6 is a sectional view on line 6—6, Figure 5.

Figure 7 is a fragmentary isometric view of a slightly modified embodiment of the invention of that seen in Figure 6.

Figures 8 and 9 are fragmentary sectional views of parts seen in Figure 6 showing the interlock between the strip in the bottom of the channel of the window frame and the demountable side of the channel.

1 designates a window frame and 2 the framing of the structure formed with a window opening 3 in which the window frame 1 is mounted. In the form shown in Figure 1, the window is provided with an upper and lower sash, one of which, as the lower sash 4, is capable of being raised and lowered, and in the construction shown in Figure 1, only the uprights or stiles of the window frame need to be of the construction about to be described.

In Figures 1, 2, 3 and 4, the portions of the frame designated 1 are the upright members of the frame. Each of these frame members 1 confines a channel and comprises a body including one side 5 of the channel and the bottom 6 of the channel and a demountable side 7 opposed to the side 5. The bottom 6 of the channel is provided with a depressed portion 8 extending

lengthwise thereof and with a shoulder 9 at the outer edge of the depression toward the demountable side 7. The body is secured to the vehicle structure in any suitable manner, as by screws 10 extending through the bottom 6 into the frame 2. 5

11 is a member in the channel for coacting with the sash. In the form shown in Figures 1, 2, 3 and 4, in which the sash is slidably mounted, the member 11 is a guide member for the sash 4, it being here shown as provided with a rib 12 extending into a groove formed in a non-metallic U-shaped lining 13 located in a channel in each edge of the sash 4. 10

14 is a resilient compression cushion or pad interposed between the member 11 and the bottom of the channel member 1 and cushioning the member 11 and serving to compensate for misalignments in the framing 2 of the window opening or in the sash or any other misalignments, so that the sash raises and lowers uniformly under all conditions, the cushion or pad 14 extending the full length of the guide member 11 or member 1. It is usually a strip of sponge rubber. 15

The demountable side 7 and the body of the frame member 1 are formed with means for interlocking upon bodily movement of the member 7 substantially flatwise into normal or operative position, or transversely of the channel or sash, and as here shown, the demountable side 7 is formed with an angular flange 15 for entering 20 the depressed portion of the bottom 6 under the pad 14, and this flange is formed with spaced apart offsets or shoulders 16 for snapping into openings 17 in the depression in the bottom 6, when the demountable side 7 has reached its normal position, the demountable side 7 compressing 25 against the edge of the pad 14, which projects slightly beyond the edge of the guide member 5, as seen in Figure 4, until the pad is compressed by the demountable side 7, as the side 7 is pressed 30 and snapped into its normal position. When the side 7 is in normal position, the guide member 11 is not tightly clamped between the sides 5 and 7, but is capable of a sliding movement during raising and lowering of the sash, while compensating 35 for misalignments. The padding exerts a substantially uniform outward pressure against the guide member 5. 40

By reason of the interlocking shoulders 16 and openings 17, the demountable side 7 is readily 45 placed in position without the use of screws and the like. It may be demounted by inserting a pointed tool as a screw-driver at A between the outer edge of the demountable side 7 and the bottom 6 and prying thereon until the shoulders 16 50 are lifted out of the openings 17. 55

The essential feature of this invention is the construction by which the demountable side of the channel may be readily replaced and removed and held in position without screws in combina- 60

tion with a resilient padding for cushioning the sash.

In Figures 5, 6 and 7, a window construction is shown in which the sash is stationary and entirely surrounded by a resilient compressible cushion. Also, the sash is shown as a double one with two glass panes 20 and 21 spaced apart with a sealed space between them. 23 is a sash frame usually of metal and the margins of the glass pane are mounted in a rubber seat 24 located within the channel in the frame 23. 25 is a spacer between the glass panes. The window frame, which is mounted in the window opening, is substantially of the same general construction as that shown in Figure 4 and comprises a body including a side 26 and a bottom portion 27 and a demountable side 28. 29 is the U-shaped mounting member, usually of rubber, enclosing the sash frame 23 and having beads or lips at 30 and 31 pressing against the margins of the panes 20 and 21 outside of the joint between the glass panes and the sash frame 23, to seal the joints and serve as an additional precaution to opening the space between the glass panes to the outer air. 32 is a cushion or pad, corresponding to the cushion 14 (Figures 2 and 4), this extending entirely circumferentially around the frame 23. 33 is an additional cushion of sponge rubber located to cushion the sash against lateral shocks. It is shown as interposed between one side of the frame 23 and the contiguous side of the member or mounting 29. The demountable side 28 is practically the same construction as that shown in Figure 4, it having an angular flange 34, corresponding to the angular flange 15 (Figure 4). The offsets or shoulders 35, corresponding to the offsets or shoulders 16 (Figures 3 and 4) snap into openings 37 in a strip 38 instead of in openings in the bottom 27 of the body of the window frame 26. The shoulders 35 interlock with the openings 37 in the strip 38, when the demountable side 28 is pressed into normal or operative position.

In the form shown in Figure 6, the demountable side 28 does not compress against the cushion 32 but compresses against one side of the member or mounting 29, which in turn presses against the resilient compressible cushion 33. The bottom of the window frame is secured to the car framing, as in Figure 1, as by screws 40, and usually a heat insulating strip 41 overlies the bottom of the channel of the window frame. This is held in position by the strip 38 overlying the insulated strip 41 and secured to the bottom of the channel of the window frame, as by rivets 43. The demountable side 28 is usually formed in sections which abut against each other at 45 (Figure 5). The two side sections 28^a are placed in position, after the top and bottom sections are mounted in position, and also in demounting, the sections 28^a are first demounted.

In Figure 7, the pad, corresponding to the pad 14, is shown as a corrugation 48 formed in the bottom of the U-shaped mounting 29 and the demountable side 49, corresponding to the side 7 or 28 (Figures 2 and 6) is formed with an outwardly extending angular flange 50, which enters into an outward extension 51 of the bottom 52 of the channel of the window frame. The extension 51 is provided with an angularly extending shoulder 53 against which the edge of the flange 50 abuts at 54 when in normal position, and the flange 53 is formed with notches 55 at intervals for the insertion of a pointed tool for use in demounting the side 49. Also, one of the beads 31 of the U-shaped member or mounting 29 is

formed with a shoulder at 56 against which the upper edge of the demountable side 49 abuts, when in normal position.

In any form of the invention, the demountable side is moved into normal position by a bodily movement and snaps into interlocking engagement with the bottom of the channel of the body of the frame member of the window frame by a bodily movement transversely of the window frame or sash and cushions against the cushioning means for the sash.

What I claim is:

1. In a window construction, the combination of a window frame formed with a channel having a body including one side and the bottom of the channel and a demountable side, a sash in the frame, a member in the channel for coacting with the sash to hold the same, a resilient compressible pad between the bottom of the channel and the opposing face of said member and coacting therewith throughout the length of said member and the channel, the demountable side of the channel having means for interlocking therewith upon movement of the demountable side inwardly into normal position.

2. In a window construction, the combination of a window frame formed with a channel having a body including one side and the bottom of the channel and a demountable side, a sash in the frame, means in the channel coacting with the sash to hold the same including a resilient compressible pad in the bottom portion of the channel and extending throughout the length of the channel, the demountable side of the channel coacting with said pad and having means extending under the pad for interlocking with the bottom of the channel, upon movement of the demountable side inwardly, into normal position in a direction transversely of the channel, and held in interlocking position by the pad.

3. In a window construction, the combination of a window frame formed with a channel having a body including one side and the bottom of the channel and a demountable side, a sash in the frame, means in the channel coacting with the sash to hold the same including a resilient compressible pad located in the bottom portion of the channel and extending throughout the length of the channel, the demountable side being formed with an angular flange extending between the pad and the bottom of the channel, the bottom of the channel and said flange having means for interlocking upon movement of the demountable side inwardly into normal position in a direction transversely of the channel.

4. In a window construction, the combination of a window frame formed with a channel having a body including one side and the bottom of the channel and a demountable side, a sash in the frame, means in the channel coacting with the sash to hold the same including a resilient compressible pad extending lengthwise of the channel, the demountable side compressing the pad and having an angular base flange overlying the bottom of the channel, the bottom and the flange having means for interlocking upon bodily movement of the demountable side into normal position in a direction transversely of the channel and being held in normal position by the action of the pad.

5. In a window construction, the combination of a window frame formed with a channel having a body including one side and the bottom of the channel and a demountable side, a sash in the frame, a member in the channel for co-

acting with the sash to hold the same, a resilient compressible pad between the bottom of the channel and the opposing face of said member and extending throughout the length of said member 5 and the channel, the demountable side of the channel having means for coacting with the body of the channel for interlocking therewith upon movement of the demountable side inwardly into normal position, the demountable side compressing 10 against one edge of said pad.

6. In a window construction, the combination of a window frame formed with a channel having a body including one side and the bottom of the channel and a demountable side, a sash in the frame, a member in the channel for coacting with the sash to hold the same, a resilient compressible pad between the bottom of the channel and the opposing face of said member and coacting therewith throughout the length of said member 15 and the channel, the demountable side of the channel having means for coacting with the body of the channel for interlocking therewith upon movement of the demountable side inwardly into normal position, the demountable side having an 20 angular flange extending under the pad between the pad and the bottom of the body, the flange and the bottom having locking means for coacting, when the demountable side is mounted in position.

30 7. In a window construction, the combination of a window frame formed with a channel having a body including one side and the bottom of the channel and a demountable side, a sash in the frame, a member in the channel for coacting with the sash to hold the same, a resilient compressible pad between the bottom of the channel and the opposing face of said member and coacting therewith throughout the length of said member and the channel, the demountable side of the channel having means for coacting with the body of the channel for interlocking therewith upon movement of the demountable side inwardly into normal position, the demountable side compressing 35 against one edge of said pad, the demountable side having an angular flange extending under the pad between the pad and the bottom of the body, the flange and the bottom having locking means for coacting, when the demountable side is mounted in position.

40 8. In a window construction, the combination of a window frame formed with a channel having a body including one side and the bottom of the channel and a demountable side, a sash in the frame, a member in the channel for coacting with the sash to hold the same, a resilient compressible pad between the bottom of the channel and the opposing face of said member and coacting therewith throughout the length of said member and the channel, the demountable side of the channel having 45 means for coacting with the body of the channel for interlocking therewith upon movement of the demountable side inwardly into normal position, the demountable side having an angular flange extending under the pad between the pad and the bottom of the body, the bottom of the body being formed with depressions and the flange with 50 projections for snapping into the depressions, when the demountable side is in normal position.

45 9. In a window construction, the combination of a window frame formed with a channel having a body including one side and the bottom of the channel and a demountable side, a sash

50 slidably mounted in the frame, a guide member slidably mounted in the channel between the sides thereof, the guide member and the sash having means for slidably interlocking, a resilient compressible pad in the channel between the bottom thereof and the guide member, the demountable side of the channel having means for coacting with the body of the channel and the pad and interlocking therewith upon movement of the removable side inwardly into normal position and held in interlocking position by the pad.

55 10. In a window construction, the combination of a window frame formed with a channel having a body including one side and the bottom of the channel and a demountable side, a sash slidably mounted in the frame, a guide member slidably mounted in the channel between the sides thereof, the guide member and the sash having means for slidably interlocking, a resilient compressible pad in the channel between the bottom thereof and the guide member, the demountable side of the channel having means for coacting with the pad and the body of the channel and interlocking therewith upon movement of the demountable 20 side inwardly into normal position, said pad extending the full length of the guide member and the channel, and the demountable side compressing against the contiguous edge of the pad, when said side is in its normal position, and the guide member being slidable between the sides of the channel toward and from the open side thereof.

30 11. In a window construction, the combination of a window frame formed with a channel having a body including one side and the bottom of the channel and a demountable side, a sash slidably mounted in the frame, a guide member mounted in the channel and slidably between the sides thereof and toward and from the open side of the channel; a resilient compressible pad in the channel between the bottom thereof and the guide member, the demountable side of the channel having an angular flange for extending between the pad and the bottom of the channel and the flange in the bottom of the channel having means for interlocking when the demountable side is in 35 normal position, the pad extending lengthwise of the guide member and the channel and the demountable side compressing against the contiguous edge of the pad when said side is in normal position.

40 12. In a window construction, the combination of a window frame formed with a channel, and a sash mounted in the frame, and a member in the channel coacting with the sash for holding the same, the channel comprising a body including a side and a bottom and a demountable side, a resilient compressible cushion interposed between the bottom of the channel and the sash mounting, and a resilient compressible cushion interposed between the side of the sash and one of the sides of the channel, the demountable side having an angular base flange for lapping the bottom of the channel, and said flange and the bottom of the channel being formed with means for interlocking and holding the demountable side in normal position, upon movement of the demountable side bodily into normal position in a direction at a right angle to the plane of the sash.

RUSSELL B. NELSON.
